DIAPER PANTS AND PAD FOR SAME

Charles F. McKhann, Bratenahl, and George A. Bricmont, Berea, Ohio, assignors to Diapette, Inc., Bratenahl, Ohio, a corporation of Ohio

Application November 17, 1948, Serial No. 60,482

1 Claim. (Cl. 128—290)

1

This invention relates to improvements in diaper pants and a pad for use in the same.

One of the objects of the present invention is to provide improved diaper pants to be used generally on infants wherein the pants provide a holding device of novel character for an absorbent pad of novel shape, thus providing a device rendering it easy to care for an infant, to keep the infant comfortable, and to avoid rashes or other irritations around the perineum and associated parts.

Another object of the present invention is to provide a novel combination of diaper pants and an absorbent pad therefor whereby a large reservoir is provided at the point remote from the urino-genital parts of the infant with means for providing a wicking action to transmit liquid from the infant to the reservoir.

Still another object of the invention is to provide a pouch of form tapering downwardly on the outside of the pants both forwardly and backwardly of the infant and a pad of complementary shape which is prevented by coaction with the pouch from sliding down and bunching up between the legs of the infant.

Other objects and advantages of the present invention will be apparent from the accompanying drawings and description, and the essential features thereof will be set forth in the appended claim.

In the drawings,

Fig. 1 is a front elevational view of a pair of diaper pants embodying our invention;

Fig. 2 is a rear elevational view of the same;

Fig. 3 is a transverse sectional view taken along the line 3—3 of Fig. 1;

Fig. 4 is a perspective view of one type of pad adapted to be used in the device of Figs. 1, 2, and 3, while

Fig. 5 is a view of another type of pad and method of making the same.

In Figs. 1, 2, and 3, we have shown a pair of diaper pants which are somewhat similar to pants disclosed in our copending application Serial No. 48,632, filed September 10, 1948, now abandoned, to which reference may be had for a more complete description of the broad use of the invention.

The device shown here when laid out flat would be generally of I-form having broad waist encircling portions 10 and 11 at opposite ends of the device having overlapping ears 10a and 11a which may be secured together around the waist of the infant by any suitable securing means such as the safety pins 12 indicated.

2

The central portion of the device is narrow as indicated at 13 to pass through the crotch of the infant. This device thus provides holes 14 and 15 at opposite sides through which the legs 5 of the infant extend when the diaper is fastened in place. Elastic may be utilized around the waistband and around the leg openings as described in our above mentioned copending application so as to make the garment fit snugly.

10 A moisture-proof pouch 16 is provided on the outer side of the garment and extending from approximately the waistline of the infant in front to a point well above the anus in the rear. Generally the basic garment will be made of 15 suitable cloth and the moistureproof pouch will be made of a Vinylite plastic or rubber-like material or any other suitable material preferably one which may be stitched to the base garment. All of these parts are properly sewed together 20 but that sewing is not shown in the drawings for the sake of clearness. There is an opening 17 provided adjacent the perineum of the wearer and preferably the moistureproof material of the pouch is folded about the edges of the basic 25 cloth member around the perimeter of the opening 17 as indicated at 18 in Fig. 3. An absorbent pad 19 is provided in the moistureproof pouch to receive body discharges from the infant.

30 As clearly seen in Figs. 1 and 2, the pouch 16 is considerably wider at the front end 16a and at the rear end 16b than it is at the crotch portions 16c. A pad of double wedge form as shown in Fig. 4 or Fig. 5 is placed inside of the pouch 16 as indicated at 19 in Fig. 3. Referring to Fig. 4, the pad 19' is of a width at its front end 20a and at its rear end 20b and at its central portion 20c generally of approximately the same dimensions as 16a, 16b, and 16c respectively.

40 Several things result from the above construction. The pad 19' is obviously narrower and less bulky where it passes through the crotch of the infant. At the same time the wide front and rear ends 20a and 20b respectively, provide a large reservoir for absorbing liquid. The pad 19' is of such a character that it will provide a wicking action to transmit the moisture from the points adjacent 20c to the ends of 50 the pad. At the same time the fact that the ends 20a and 20b fit into the wide portions 16a and 16b and above the narrower portions of the moistureproof pouch, prevent the ends of the pad from slipping downwardly. In other words, 55 the corresponding double wedge form of the pad

and the moistureproof pouch provide an automatic holding device whereby the pad is always held in position.

While the pad 19' of Fig. 4 may be molded or cut to the form shown, in Fig. 5 we have shown another manner of forming a pad usable in this type of device. Here the pad 19'' may be formed from a block or sheet 21 generally rectangular in form. A long strip of gauze-like material 22 is then wrapped around the block 21 beginning at one end with little or no tension upon the gauze as it is wound at that point. As the winding progresses toward the central portion of the pad, the tension is gradually tightened on the gauze-like strip so that the pad is gradually constricted to become narrower and narrower to the central portion of the device as indicated at 23 in the drawings. Obviously, the pad of Fig. 5 is only half formed and the winding will continue to the right hand end of the block 21, the tension being gradually lessened allowing the pad to become wider and wider until the right hand end is of full width as was the left hand end where the winding began. The pad of 19'' will fit in the device shown in Figs. 1, 2, and 3, in the same manner as the pad 19' of Fig. 4.

The pads 19' and 19'' may be of any suitable absorbent material and will generally be of cotton, cellulose, cellucotton, or other similar material. Obviously, the material for forming the pad of Fig. 4 must have the ability to hold itself together in the shape there shown either as molded or as cut out of sheet material. The material of

Fig. 5 may be less strongly held together and may be any suitable material which will remain in a block or sheet or bale long enough to be wrapped by the gauze-like material 22. To repeat, the pads shown in Figs. 4 and 5 are self-supporting; that is, the ends will be held up by engagement with the sides of the converging pockets, and the pads will maintain their shape by virtue of the material used (Fig. 4), or by virtue of the gauze-like wrapping (Fig. 5).

What we claim is:

A pad for use in diaper pants comprising absorbent material of a length adapted to pass through the crotch of a wearer and to extend partly up the front and back of the wearer, a cloth wrapping about said absorbent material, and said wrapping compressing said material to a greater degree in the midportion of said pad than at the ends thereof.
